UNITED STATES PATENT OFFICE.

JOHN MARTIN, OF IMPERIAL, CALIFORNIA, ASSIGNOR OF ONE-HALF TO JOSE DE BARROS, OF IMPERIAL, CALIFORNIA.

RAPID-FIRING GUN.

1,285,765.

Specification of Letters Patent. Patented Nov. 26, 1918.

Application filed May 21, 1917. Serial No. 170,033.

To all whom it may concern:

Be it known that I, JOHN MARTIN, a citizen of the United States, residing at Imperial, in the county of Imperial and State of California, have invented new and useful Improvements in Rapid-Firing Guns, of which the following is a specification:

This invention relates to ordnance and particularly pertains to a rapid-firing gun. 10 Another object of this invention is to provide a rapid-firing gun which is motor driven and will thus act positively and independently of any impulse produced by the explosion of the shells within the gun, thus insuring that the gun may be fired continuously and with great precision.

Another object of this invention is to provide a breech block and firing mechanism which is possessed of few parts so arranged as to permit the ammunition to be quickly placed in the barrel and to be positively fired by a continuously operating breech mechanism.

Another object of this invention is to provide a shell ejector which will engage the rims of the exploded shells and throw them from the gun prior to re-loading.

Another object of this invention is to provide a mechanism of few parts, of simple operation for placing the ammunition within the gun and carrying it from a shell magazine.

Another object of this invention is to provide a shell magazine of simple construction which may be easily connected with the breech portion of the gun and will positively deliver the shells successively to the loading mechanism.

It is a further object of this invention to provide a gun of the above class which is compact in its design and construction and will operate continuously without great danger of requiring repair.

Other objects will appear hereinafter.

25 The invention is illustrated, by way of example, in the accompanying drawings in which:

Figure 1 is a view in side elevation illustrating the gun as completely assembled, and as having parts of its cooling jacket and the shell magazine broken away to more clearly show their construction.

Fig. 2 is an enlarged view in longitudinal section and elevation illustrating the breech block, the shell feeding mechanism and the

magazine therefor, and the disposition of these various elements in relation to the barrel of the gun.

Fig. 3 is a view in transverse section as seen on the line 3—3 of Fig. 2 and as illustrating the firing-pin release detent and its relation to the bolt.

Fig. 4 is a view in plan illustrating the manner in which the firing-pin release detent is actuated by the movement of the bolt in the breech block.

Fig. 5 is a small view in plan illustrating the entire gun and particularly disclosing the shell ejector and the breech block operating mechanism.

Fig. 6 is a fragmentary plan analogous to Fig. 5, parts being broken away and shown in section to show the shell extractor.

Referring more particularly to the drawings, 10 indicates a base block which is formed with a base plate 11 by which the entire field piece may be fastened to a gun base. This block is hollow and incloses electrically operated apparatus for revolving the gun, as will be hereinafter described. 15 Formed upon the block is a ball race 12 upon which the circular pedestal 13 of a gun carriage 14 is revolvably mounted. A central vertical king post 15 is fixed to the top of the base block 10 and is in concentric arrangement with the ball race 12. The upper end of this post is threaded to receive a nut 16 which holds the carriage upon the ball race and permits it to rotate horizontally upon ball-bearings 17 which are mounted upon the race. The circular base portion of the carriage is formed with a spur gear 18 which extends around its outer periphery and is in constant mesh with a driving gear 19. This gear is fixed 20 to the upper end of a driving shaft 20 which extends vertically through a tap in the base block and is engaged by the actuating apparatus in the block. The gun carriage

comprises a pair of parallel vertical arms 21 which form a cradle for the gun. These arms are provided with bearings 22 within which the trunnions 23 of the gun are rotatably secured. It will be understood that by this pivotal arrangement the gun may 25 swing vertically. In order to produce vertical movement of the gun a segmental gear 24 is fixed to the side of the gun and is in constant mesh with a gear 25 by which it is actuated. This gear is fixed upon a hori- 30

zontal shaft 26 which extends into a range finder case 27.

The gun proper is composed of a barrel 28 which is provided at its outer end with a sight 29. The rear half of the barrel is formed with circumferentially extending fins 30 which are spaced in relation to each other and provide additional heat radiating surface for the firing chamber of the gun. 10 These fins are air cooled and are inclosed within a cooling jacket 32 which is opened at its forward end, as indicated by the numeral 33. The rear of the cooling case is formed with an air passage-way 35 which 15 permits the air from the case to be conducted to the breech block and will cause it to create a draft therearound which will act in a beneficial manner to lower the temperature of the block.

20 The rear end of the barrel is, of course, open to provide a firing chamber 36 within which shells 37 may be placed. These shells are carried within a detachable shell clip, or magazine 38 which provides a container for a plurality of shells arranged side by side and held in their uppermost position by a feed plate 39. This plate is borne against by an expansion spring 40, as particularly shown in Fig. 2 of the drawings. 25 The outer casing of the magazine is fitted with a lug 41 which is engaged by a locking catch 42. This catch is normally held beneath the lug 41 by means of a spring 43 and may be swung outwardly from this position by an actuating pin 44. This pin extends outwardly through a slot 45 in the spring clip mounting.

The spring clip mounting is formed integral with a shell feeding case 46 which 40 is provided with an inclined bore 47 disposed beneath the breech block. This bore extends at right-angles to the spring clip and is therefore in longitudinal alinement with the shells which are successively moved 45 into the forward end of the bore. As shown in the drawings, the longitudinal axis of the bore 47 converges with the longitudinal axis of the gun barrel and at substantially the same point that the end of the shell occupies 50 when it is in the firing chamber. Reciprocally mounted within the rear end of the bore 47 is a loading plunger 48. This plunger is supplied with an actuating pin 49 which extends outwardly from the one 55 side of the bore and is engaged in a pivotal manner by the end of an elevating arm 51. This arm extends along the side of the magazine and is secured to the crank 53, said crank being fixed upon the end of the shaft 60 55 of the motor 54. The motor 54 is mounted directly beneath the rear end of the barrel and in front of the magazine.

Formed integral with the loading mechanism housing 46 and positioned thereabove 65 is a breech 57. This block is stationarily

disposed in longitudinal alinement with the barrel of the gun and is spaced a distance from the rear end thereof substantially equal to the length of the shell 37. Reciprocably mounted within this block is a 70 breech bolt 58 which has downwardly extending lugs 59 by which it may be moved. The pivot pin 60 is fixed in the lugs 59 and extends from the opposite side of the breech block from the pin 49, and a shifting rod 75 61 connects the pin 60 to the crank 63 fixed upon the opposite end of the motor shaft 55 from the crank 53. The cranks 53 and 63 are set diametrically opposite each other so that the plunger 48 and the breech bolt 80 58 work in opposite directions, that is, when the breech bolt 58 is withdrawn, the plunger 48 advances a cartridge into the firing chamber, and when the plunger 48 withdraws, the breech bolt moves against the 85 cartridge and fires the cartridge. Positioned within a longitudinal bore 64 extending the length of the breech bolt 58 is a firing pin 65, the point of which passes through a small opening at the end of the 90 bolt and is adapted to strike the percussion cap with which the ends of the shells are fitted. This pin is driven by means of a coil spring 66 arranged around the stem 67 of the pin. This stem extends through an end bearing 68 which is threaded into the rear end of the breech bolt 58 to retain the spring 66. Fastened to the end of the stem 67 is a catch 69 which extends upwardly and encounters a detent 70 which is fastened upon a trip shaft 71 rotatably secured within the top of the breech block. Reference being had to Fig. 4 it will be seen that the detent is formed with a square 95 rear face and an inclined side face, while the catch is formed with an inclined side face and a square front face. The inclined faces of the two members are adapted to bear against each other when the catch moves rearwardly and will thus swing the 100 detent to one side, thereafter to lock with it when it is swung in front of the catch by a torsion spring 72. The forward end of the trip shaft 71 is provided with a finger 73 which extends downwardly in the path 105 of travel of a tripping cam 74. This cam is formed as a projection upon the upper face of the breech bolt 58 and is of a configuration particularly shown in Fig. 4 of the drawings. It will thus be seen that when 110 the catch 69 is engaged by the detent 70, it will be held while the pitman rod 61 draws the bolt forward, thus compressing the spring 66, and that when the finger 73 is encountered by the cam 74 the catch 69 115 will be released.

In order that the moving parts of the firing and loading mechanism may be supplied with lubrication, an oil reservoir 75 120 is formed beneath the breech block and 125 130

above the loading mechanism. This reservoir is filled through a filling opening 76 and is formed with a series of lubricating ducts which extend to the various bearings 5 of the apparatus and provide it with adequate lubrication.

Positively operated means are provided within the breech block mechanism to remove the shells from the firing chamber after their explosion. This device consists of 10 ejector fingers 77 which are fastened to the sides of the breech bolt 58, as particularly shown in Fig. 6 of the drawings. These fingers are semi-rigid and are provided with 15 hooks 78 which pass into small cavities 79 at the sides of the shell to engage the shell rim. In this manner the shell will be positively engaged and the back movement of the bolt will cause it to be withdrawn from the barrel. 20 When the shell is withdrawn from the barrel by the retreat of the breech bolt 58, the plunger 48 advances another cartridge upwardly and throws the empty shell upwardly.

25 It will be understood that the gun barrel might be swung upon its trunnions to various angles to the horizontal and that the gun carriage might also be swung to assume various angles throughout a horizontal plane, both of which operations would be effected mechanically.

In operation, the gun is set up on its base at an advanced position in the field, such as a first line trench. When in place the shell 35 magazine 38 is snapped into engagement with the catch 42. When the range has been found the motor 54 is started. This motor will rotate the cranks 53 and 63 in the direction indicated by the arrow —a— in Fig. 40 2. As these cranks rotate from the position shown in Fig. 2, the breech bolt 58 will be moved rearwardly within the breech and the plunger 48 will move along the loading bore 47. As the bolt clears the upper end of the 45 bore, the loading plunger 48 will elevate the uppermost shell 37 in the magazine and cause it to be projected into the firing chamber of the barrel. Continued rotation of the 50 cranks will cause the retraction of the loading plunger 48 and permit a second shell to be raised in preparation for being fed through the barrel. While this loading operation is taking place, the bolt 58 moves rearwardly into the breech and the catch 69 55 upon the end of the firing pin stem 67 is engaged by the detent 70. The return movement of the bolt 58 then takes place. This movement occurs at an interval which will cause the shell 37 to be driven home into the 60 firing chamber 36 where it will be held. When the bolt 58 has been drawn against the end of the shell 37, the cam 74 upon the upper face of the bolt and within the breech will strike the trip finger 73 mounted upon 65 the trip shaft 71. This movement will rock

the trip finger 73 and cause the detent 70 to swing out of an obstructing position before the catch 69. The spring 64 will then be released, as well as the firing pin 65 and the pin will move forward with great force 70 to strike the percussion cap within the end of the shell, thus causing an explosion. Simultaneous with the forward movement of the breech bolt 58, the shell ejector 77 will 75 engage the rim of the shell and as the bolt is again retracted will withdraw the shell and throw it out of the gun. This will clear the firing chamber for action which will take place as soon as the loading plunger 48 delivers another shell from the magazine. 80

It will thus be seen that the gun here disclosed may be operated in a positive and continuous manner by a positively acting driving mechanism, and furthermore that the gun may be readily adjusted to any desired inclination and position throughout a horizontal plane. 85

While I have shown the preferred construction of my rapid-firing gun as now known to me, it will be understood that various changes in the combination, construction and arrangement of parts may be made by those skilled in the art without departing from the spirit of my invention. 90

I claim:

1. In a rapid-firing gun, a barrel having a firing chamber in its rear end, a shell feeding case extending backwardly and downwardly from the firing chamber and having an inclined bore leading to the firing chamber, a shell clip mounted in the shell feeding case and discharging to the bore, a loading plunger in the rear end of the bore, an actuating pin extending outwardly from the loading plunger through the shell feeding case, a shaft mounted transversely below the firing chamber, a crank upon this shaft, and a pitman connecting the crank to the actuating pin. 100

2. In a rapid-firing gun, a gun barrel having a firing chamber at its rear end, a shell feeding case extending downwardly and backwardly from the firing chamber, means for feeding shells to the firing chamber, a breech extending upwardly from the shell feeding case in line with the barrel and spaced a distance from the rear end of the barrel, a breech bolt mounted in the breech, a lug extending downwardly from the breech bolt, a shaft mounted transversely below the firing chamber, a crank upon this shaft, and a pitman connecting the crank to the lug; so that as the crank rotates the breech bolt will reciprocate. 110

3. In a rapid-firing gun, a gun barrel having a firing chamber at its rear end, a shell feeding case extending downwardly and backwardly from the firing chamber, means for feeding shells to the firing chamber, a breech extending upwardly from the shell feeding case, 120

125

feeding case in line with the barrel and spaced a distance from the rear end of the barrel, a breech bolt mounted in the breech, a lug extending downwardly from the 5 breech bolt, a shaft mounted transversely below the firing chamber, a crank upon this shaft, a pitman connecting the crank to the lug; so that as the crank rotates the breech bolt will reciprocate; there being a longitudinal bore 10 extending the length of the breech bolt; a firing pin in the bore, a stem extending backwardly from the firing pin through the end of the breech bolt, a spring upon the stem for operating the firing pin, 15 a catch extending from the rear end of the

stem, a trip-shaft mounted in the breech parallel with the breech bolt, a detent upon the rear end of the trip-shaft and extending into the path of the catch; said detent having a square rear face and an inclined side 20 face and said catch having an inclined side face and a square front face; a spring upon the trip-shaft, a finger at the forward end of the trip-shaft, and a tripping cam extending from the breech bolt to engage the 25 finger.

In testimony whereof I have signed my name to this specification.

JOHN MARTIN.
